By his Attorney,
Nelson W. Standish.

UNITED STATES PATENT OFFICE

ALBERT W. DOSTIE, OF AUBURN, MAINE, ASSIGNOR TO UNITED SHOE MACHINERY CORPORATION, OF PATERSON, NEW JERSEY, A CORPORATION OF NEW JERSEY

FASTENING-SUPPLYING MECHANISM

Application filed September 27, 1926. Serial No. 137,957.

My invention relates to mechanisms for supplying fastenings to the mechanism which is to transfer them to the point of utilization. The invention is herein illustrated as applied to a nail-distributor delivering to the loading mechanism of a heel-attaching machine.

In nail-distributors of heeling machines, it is a common practice to start the mechanism in operation for nail-delivery when the loader-block, in which the nails are to be transferred to the die-block of the heeler, reaches a receiving position. A distributing mechanism organized to act in this manner is made the subject of United States Letters Patent No. 1,005,303, granted October 10, 1911, on application of Joseph H. Pope. In this, a clutch, released upon the arrival of the loader-block beneath the foot-plate in which the nail-delivering tubes terminate, acts through a chain of elements, including gearing, a clutch, cam, lever, connecting-rod and crank, to impart to the discharge-roll of the distributor its movement by which it delivers nails received directly from the movable raceways upon which they are supported in series end to end. It is sometimes found that a highly efficient operator is so rapid in his movements that he will have a shoe heeled, removed from the jack and another shoe and heel ready for nailing before a load of nails can be delivered from the distributor and transferred to the die-block ready for driving. There may consequently be forced upon him a series of intervals of idleness, resulting in a considerable cutting down of his productive capacity. The delay in nail-delivery is largely due to the time necessary to bring about the engagement of the clutch and to transmit from this driving device movement through the interposed elements to the discharge device. An object of my invention is to eliminate this mechanical lag, and insure the prompt supply of nails to the transferring mechanism. This I accomplish by transmitting movement to the discharge device from the loading or transferring mechanism, thus avoiding the necessity for control of an external source of power and the application

of this power, with the consequent delay. By causing the loading mechanism to act directly upon the discharge device, the latter is started into action coincidently with the arrival of the loader-block at the receiving position. In the specific form of my invention herein disclosed, such a member as a rod is moved vertically by the loader-arm, and has a constantly effective connection to the discharge-roll of the distributor, by which connection the rectilinear movement of the member is transformed into oscillation at the roll.

The accompanying drawing shows one of the several embodiments which this invention may have.

Fig. 1 being a broken side elevation of a heel-attaching machine, with which is associated my improved supplying mechanism; and

Fig. 2, a partial top plan view of said mechanism.

At 10 appears the frame of a heel-attaching machine, the jack 12 of which presents a shoe to be heeled to nail-inserting or driving mechanism 14. Mounted upon the upper portion of the frame 10 is a nail-distributor, designated as a whole by the numeral 16, and having journaled to oscillate transversely across the delivery-end of its frame 18 a roll 20, by which nails are received in successive loads from raceways 22, and discharged to tubes 24. This distributor may, in its general structure, be identical with that of the previously mentioned patent, and will therefore not be described in detail. The tubes of the distributor terminate in a foot-plate 26, the openings of which correspond in arrangement to the nailing design to be employed. Into alignment with these foot-plate-openings may be moved the nail-receiving openings of a loader-block 28 carried by an arm 30 arranged to oscillate between this receiving position and its delivering position over the die-block-openings at the nailing mechanism 14.

After each of its discharging oscillations, the roll 20 receives a fresh load from the raceways, which may be continuously vibrated from a power-shaft 32 of the distrib-

utor. It is from this shaft that the discharge-roll of Pope receives movement through the train of elements which have been hereinbefore outlined. To cause the immediate delivery-movement of the roll when the loader-block reaches its receiving position beneath the foot-plate, I may utilize a rod 34, which heretofore has been employed to trip the clutch for actuating the discharge-roll. This rod is mounted to reciprocate vertically in a guide bracket 36 projecting from the frame 10, and is raised by an inclined surface 38 upon the loader-arm only at a time when the loader-block openings and foot-plate-openings are approaching alinement. To the threaded upper end 40 of this rod 34 is attached between nuts 42, 42 an offset rod-section 44, which may be guided at its upper extremity by a link 45 pivoted to the distributor-frame 18. The rod-section 44 is joined to the roll 20 by intermeshing projections and depressions, these being shown as in the form of a rack 46 upon the rod and a pinion 48 fixed upon the roll-shaft. By properly proportioning the pinion 48 and the lift imparted by the surface 38, the roll 20 may be caused to oscillate through the desired angle and discharge its load of nails into the tubes 24 as soon as the loader-block is in place to receive them. Therefore, the return-movement of the loader mechanism and its delivery to the die-block of the nailing mechanism may unfailingly anticipate the requirements of the operator. The adjustment of the effective length of the rod 34, 44, by means of the nuts 42, allows the normal relation of the discharge-roll to the delivering ends of the raceways to be varied. It should be noted that, by the connections of this invention, not only is the prompt actuation of the discharge-roll attained, but also the distributor is simplified by the removal of a number of elements, thus reducing, especially through the omission of the clutch, both the construction and maintenance costs.

Having described my invention, what I claim as new and desire to secure by Letters Patent of the United States is:

1. The combination with fastening-supplying mechanism including movable raceways each of which is arranged to support a plurality of nails lying end to end, means for moving the raceways to advance the supported nails and a discharge device situated opposite the ends of the raceways and arranged to receive fastenings in successive groups as they are advanced thereby, of mechanism movable to transfer fastenings from the discharge device of the supplying mechanism, and means for transmitting the movement of the transferring mechanism to the discharge device.

2. The combination with a nail-distribu-

tor having a movable discharge device, of loading mechanism movable into nail-receiving position at the distributor, and means arranged to start the discharging movement of the device coincidently with the arrival of the loading mechanism at the receiving position.

3. The combination with a nail-distributor having raceways and an oscillatory discharge-roll to which nails are delivered by the raceways, of loading mechanism movable into position to receive nails falling from the discharge-roll, a member movable vertically by the loading mechanism, and constantly effective connections between the member and discharge-roll arranged to transform the rectilinear movement of the member into oscillation of the roll.

4. The combination with a nail-distributor having an oscillatory discharge-roll, of loading mechanism movable into nail-receiving position at the distributor, a member movable by the loading mechanism, means arranged to vary the effective length of the member, and constantly effective connections between the member and discharge-roll arranged to oscillate said roll.

5. In a nailing machine, nailing mechanism, nail-distributing mechanism having an oscillatory discharge-roll, a loader-arm provided with a nail-block movable between the distributing and nailing mechanisms, a guide situated above the loader-arm, a rod mounted to reciprocate in the guide, said rod being movable by the loader-arm and having a projection, a link connecting the rod to a relatively fixed point, and a member mounted to oscillate with the roll and engaged by the projection.

In testimony whereof I have signed my name to this specification.

ALBERT W. DOSTIE.
